DESIGN FOR A COMBINED CALENDAR, CLOCK, AND DESK UNIT

Bailey T. Bowers, Chicago, Ill.

Application September 19, 1946, Serial No. 133,411

Term of patent 3½ years

(Cl. D74—1)

To all whom it may concern:

Be it known that I, Bailey T. Bowers, a citizen of the United States and a resident of Chicago, in the county of Cook and State of Illinois, have invented a new, original, and ornamental Design for a Combined Calendar, Clock and Desk Unit, of which the following is a specification, reference being had to the accompanying drawing, forming a part thereof.

Fig. 1 is a perspective view in an open position of a combined calendar, clock and desk unit showing my new design, the printed matter shown on the calendar being merely representative of that which would appear thereon from time to time.

Figure 2 is a perspective view of the same in a closed position.

I claim:

The ornamental design for a combined calendar, clock, and desk unit, substantially as shown and described.

BAILEY T. BOWERS.
